WRITING IMPLEMENT WITH YIELDABLY SUPPORTED SCRIBING ELEMENT

Clyde R. Patterson, Riverside, Calif.

Application March 24, 1950, Serial No. 151,690

5 Claims. (Cl. 120—9)

1

This invention relates to a novel construction of writing implement such as a pen or pencil having the scribing element which is reciprocally mounted relatively to the body portion or barrel which is held in the hand so that a uniform and proper pressure will exist at all times on the point or end of the scribing element which engages the paper to prevent an excess pressure on said point or end.

Among the primary advantages of the present invention is to provide a writing implement wherein the writing will be of uniform shade irrespective of the pressure exerted by the hand holding the implement in urging it toward the paper or other surface engaged by the writing point or end and which will thereby provide a writing implement wherein the point or writing end will float freely and easily across the paper and thus relieve all strain on the hand of the writer holding the implement and resulting "writer's cramp."

Still a further object of the invention is to provide a writing implement which is capable of being readily adjusted to vary the yieldable tension on the writing end or point to accommodate the instrument to writers using different pressures when writing.

A particularly important object of the present invention is to provide a yieldable mounting especially adapted for use for resiliently mounting the ink cartridge of ball point pens to prevent an excess pressure being applied on the paper engaging ball point and which causes an unsatisfactory operation of such pen due to the fact that the ball is prevented from turning properly, too great an amount of ink is initially removed from the paper by the ball and as a result when too much pressure is thus exerted on such pen the writing has a tendency to fade, resulting in an uneven and unsightly appearance.

Various other objects and advantages of the invention will hereinafter become more fully apparent from the following description of the drawing, illustrating one presently preferred embodiment of the invention, and wherein:

Figure 1 is a side elevational view illustrating the invention embodied in a ball point-type pen;

Figure 2 is a central sectional view, partly in side elevation thereof and on an enlarged scale;

Figure 3 is a side elevational view, partly broken away, of the writing implement housing or barrel;

Figure 4 is a similar view of the ink cartridge guide;

Figure 5 is a cross sectional view thereof taken substantially along a plane as indicated by the line 5—5 of Figure 4;

2

Figure 6 is a side elevational view, partly in section of the ink cartridge;

Figure 7 is an end elevational view thereof looking from left to right of Figure 6, and

Figure 8 is an end elevational view of the assembled writing implement looking from left to right of Figures 1 and 2.

Referring more specifically to the drawing, the writing implement in its entirety and which has herein been illustrated as a ball point-type pen is designated generally 10 and includes a barrel or housing 11 which is preferably circular in cross section to provide a relatively large chamber 12. The barrel 11 has an open forward end which is internally restricted by an internal enlargement 13 thereof and is provided at its opposite end with a rear end wall 14 which is shown provided with a central opening 15.

An ink cartridge guide, designated generally 16 has a bore 17 of circular cross section and uniform diameter extending from end-to-end thereof. The guide 16 includes a relatively long tubular end 18 and forwardly thereof is provided with an externally enlarged portion or collar 19. The forward end of the guide 16, which is disposed beyond and forwardly of the collar 19 constitutes a frusto-conical portion 20 having a large rear end located adjacent the forward end of the collar 19 and combining therewith to form an annular rearwardly facing shoulder 21. The forward end of the frusto-conical portion 20 is preferably smaller in diameter than the collar 19. The tube portion 18 of the guide 16 is adapted to fit loosely in the chamber 12 and is held substantially concentric to the barrel 11 by the collar 19 which engages snugly in the restricted open forward end of the barrel 11, defined by the internal enlargement 13. The shoulder 21 seats against the open forward end of the barrel 11 so that the frusto-conical portion 20 of the guide 16 forms a tapered extension of the forward end of the barrel 11, as clearly illustrated in Figures 1 and 2. The tube 18 at its opposite, rear end is provided with diametrically aligned longitudinally extending slots 22 which preferably open outwardly of the rear end of the tube 18.

An ink cartridge, designated generally 23 includes a tube 24 which is longer than the ink cartridge guide 16 and which is reciprocally and detachably disposed in the bore 17. The tube 24 is provided with a frusto-conical shaped enlargement or head 25 at its forward end having a tapered bore 26 the enlarged end of which communicates with the forward end of the bore 27 of the tube 24 and the restricted, forward end 55 of which opens into a socket 28 in the forward

end of the head 25 and which socket 28 has a restricted open forward end, which opens outwardly of the forward end of said head 25. The socket 28 rotatably supports a small writing ball or sphere 29 more than one half of which is engaged by the socket 28 for rotatably but non-detachably supporting the ball 29 therein. The bore 27 and bore portion 26 are adapted to be filled with ink, not shown, which is fed to the sphere 29 in a conventional manner. The parts 24 to 29 and the ink cartridge 23, previously described are all of conventional construction and said ink cartridge differs from the conventional ink cartridge or ball point pen only in that it is provided adjacent its rear end with aligned openings 30 formed in the tube 24 for detachably receiving a stop pin 31, the ends of which project outwardly from the outer surface of the tube 24. With the pin 31 removed, the ink cartridge tube 24 is applied to the bore 17 before the ink cartridge guide 16 is applied to the barrel 11, said tube 24 being inserted through the bore from its forward end. The openings 30 are then aligned with the slots 22 and the pin 31 is applied, as illustrated in Figure 2, so that its ends slidably engage the slots 22 to retain the ink cartridge 23 in the guide 16.

An adjustable spring stop, designated generally 32 is detachably mounted in the barrel chamber 12 at its rear end and includes a sleeve 33 having a threaded bore 34 extending longitudinally and centrally therethrough. A threaded stem 35 threadedly engages the bore 34 and extends from the inner end of the sleeve 33 and is provided at its inner end with a head or enlargement 36 having a substantially flat face against which engages one end of an expansion coiled spring 37. The opposite end of the spring 37 abuts against a disk 38 which is of substantially the same diameter as the head 36. The opposite side of the disk 38 bears against the rear end of the ink cartridge tube 24, which projects from the rear end of the guide tube 18. The opposite, outer end of the stem 35, which is disposed normally in the threaded bore 34 is provided with a kerf 39.

The sleeve 33 and head 36 are of an external diameter to pass through the restricted bore portion of the chamber 12 as defined by the internal enlargement 13 and are initially applied to the barrel 11 so that the outer end of the sleeve 33 bears against the barrel end 14. The spring 37 is then applied to the barrel 11 after which the disk 38 is applied, all as illustrated in Figure 2. If desired, the forward end of the spring 37 may be secured to the follower disk 38 and the rear end of said spring may be secured to the face of the head 36 so that the spring and disk will form a unit with the stem 35. After the adjustable stop 32, spring 37 and follower disk 38 have been applied, as illustrated in Figure 2, the ink cartridge guide 16, assembled with the ink cartridge 23, as previously described, is then applied to the barrel 11, forwardly of the disk 38, as illustrated in Figure 2. The spring 37 will project the ink cartridge 23 forwardly of the ink cartridge guide 16 so that the ink cartridge head 25 will be spaced from the forward end of the frusto-conical guide portion 20, as illustrated in Figures 1 and 2. Accordingly, when the ball 29 is applied to a sheet of paper or other surface for writing, the pressure exerted by the hand grasping the barrel 11 and pressing the ball 29 against the paper, not shown, will cause the ink cartridge 23 to slide inwardly of the guide 16 against the action of the spring

37 so that the writing ball 29 will have a floating support relatively to the barrel 11 when in use. Thus, the ball 29 will be prevented from being pressed too hard against the paper and irrespective of the amount of pressure exerted thereon by the writer, will be maintained with the proper pressure against the paper so as to produce a free and even flow of ink from the ball 29 to the paper. As a result, the writing will be of a uniform shade and the tendency of the writing to fade will be eliminated. Furthermore, the floating support of the writing ball 29 on the paper will eliminate strain on the writing hand and the resulting "writer's cramp."

As the pressure employed by different writers varies considerably, in order to maintain the writing ball 29 in a floating position when the writing implement 10 is in use and to accommodate it to any degree of variation in pressure, the adjustable stop 32 is provided so that the tension on the spring 37 may be increased by turning the stem 35 relatively to the sleeve 33 to extend the stem relatively to the sleeve for increasing the tension of the spring 37 or the stem may be retracted relatively to the sleeve for reducing the tension on the spring 37. The tension on the spring 37 would be increased where the writer employed a heavy pressure or diminished where the writer employed a relatively light pressure in writing. This adjustment of the stop 32 may be accomplished before it is applied to the barrel 11 or while removed therefrom and may also be accomplished while the parts are in their applied positions of Figure 2 by inserting a tool, not shown, such as a small screwdriver through the opening 45 which aligns with the bore 34 to engage the kerf 39 and turn the stem 35 relatively to the sleeve 33. The frictional engagement of the sleeve 33 with the end wall 14 will permit the stem 35 to be turned in either direction relatively to said sleeve.

Various modifications and changes are contemplated and may obviously be resorted to, without departing from the spirit or scope of the invention as hereinafter defined by the appended claims.

I claim as my invention:

1. The combination with a scribing device including an elongated rigid reservoir having a writing point at one of its ends, of an elongated hollow barrel having an open forward end and an end wall at its opposite, rear end, an elongated guide secured in the open end of the barrel having a tubular portion disposed within the barrel and spaced from the barrel wall, said scribing device extending slidably through the guide and projecting beyond the ends thereof, the writing point of the scribing device extending beyond and being spaced from a forward end of the guide and the forward end of the barrel, and spring follower means mounted in the barrel between its rear end wall and the rear end of the scribing device and bearing against said scribing device for yieldably urging it forwardly of the guide for resiliently supporting the writing point thereof relatively to the barrel and guide when in use.

2. A writing implement as in claim 1, said spring follower means comprising an expansion coiled spring, a disk disposed between one end of said spring and the adjacent, rear end of the scribing element, and an adjustable spring stop formed of extensible end sections loosely disposed in the barrel between the opposite end of the spring and the end wall of said barrel.

3. A writing implement of the ball point pen-

type comprising an elongated hollow barrel having a rear end wall and an open forward end, an elongated ink cartridge guide detachably mounted in the barrel and having a restricted rear end portion disposed in and spaced from the barrel wall, said guide having a bore extending longitudinally therethrough, an ink cartridge having a tubular reservoir portion slidably mounted in and snugly fitting the guide bore and projecting beyond each end thereof and having a writing ball or point mounted in one end thereof and disposed beyond and spaced from the forward end of the guide, and spring follower means mounted in the barrel bearing against its rear end wall and against the rear end of the ink cartridge tube and yieldably urging said tube forwardly of the guide for yieldably supporting the writing ball or point relatively to the guide and barrel when in use.

4. A writing implement as in claim 3, said spring follower means including an expansion coiled spring and an extensible spring stop loosely disposed in the barrel between the spring and the rear end wall of the barrel.

5. A writing implement as in claim 3, said spring follower means including an expansion coiled spring and an extensible spring stop loosely disposed in the barrel between the spring and the rear end wall of the barrel, said spring stop being formed of retractable and extensible sections for varying the tension on the spring.
